CLAIM

The ornamental design for a wheel chock device, as shown and described.

DESCRIPTION

FIG. 1 is a perspective view of the wheel chock device;

FIG. 2 is a left side view thereof;

FIG. 3 is a right side view thereof;

FIG. 4 is a front view thereof;

FIG. 5 is a rear view thereof;

FIG. 6 is a top plan view thereof; and,

FIG. 7 is a bottom plan view thereof.

The broken lines illustrate portions of the wheel chock device in which the design is embodied that form no part of the claimed design. The hatching lines shown in FIGS. 1, 2, and 6 are for illustrating inside portions of the wheel chock device and form no part of the claimed design. The appearance of any portion of the wheel chock device between the break lines forms no part of the claimed design.

1 Claim, 6 Drawing Sheets
